Des. 189,965
Patented Mar. 28, 1961

189,965

SAFETY CLASP

Julius Harris, 434 N. Kenmore Ave., Los Angeles, Calif.

Filed Sept. 9, 1960, Ser. No. 62,081

Term of patent 14 years

(Cl. D17—3)

Fig 1

Fig 2

Fig 3

Figure 1 is a front elevation of a safety clasp showing my new design in open position;

Figure 2 is a side elevation of same; and

Figure 3 is a perspective view of the safety clasp shown in closed position.

I claim:

The ornamental design for a safety clasp, substantially as shown.
